UNITED STATES PATENT OFFICE.

ALOIS MERKE, OF NEW YORK, N. Y.

APPARATUS FOR TREATING THE SCALP.

Application filed December 11, 1922. Serial No. 603,090.

To all whom it may concern:

Be it known that I, ALOIS MERKE, a citizen of France, residing at New York, in the county of New York and State of New York, have invented certain new and useful Improvements in Apparatus for Treating the Scalp, of which the following is a specification.

This invention relates to an apparatus designed primarily for treating the scalp, although it is to be understood that an apparatus in accordance with this invention can be employed for any purposes wherein it is found applicable, and the invention has for its object to provide, in a manner as hereinafter set forth, means for generating and directing heat rays against the scalp for relaxing and opening the pores whereby a medicant applied to the scalp prior to the relaxing and opening of the pores thereof will penetrate to the roots of the hair for invigorating purposes.

A further object of the invention is to provide what may be termed a head gear for positioning on the head and embodying means for generating and directing heat rays to the area of the head within said gear for the purpose of opening the pores of the scalp, stimulation of the blood circulation, opening sweat glands, destroying bacteria, providing for the ready removal of dirt and crustaceous formations from the scalp, and further for preparing the scalp for a scientific treatment for the development of the hair bulb, papilla, glands, etc.

Further objects of the invention are to provide an apparatus for the purpose set forth, which is extremely simple in its construction and arrangement, strong, compact, durable, efficient and convenient in its use, readily assembled and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a side elevation of an appa-

ratus for treating the scalp in accordance with this invention.

Figure 2 is a front elevation.

Figure 3 is a vertical sectional view.

An apparatus for treating the scalp, in accordance with this invention comprises a head gear consisting of an upper section 1 for supporting an electrical heat generating device, and a lower section 2 for enclosing the head of a patient. The section 2 preferably extends into the former at the bottom thereof, but not necessarily so, and if desired the top of the lower section 2 can overlap the bottom of the upper section 1. The sections 1 and 2 are secured together in any suitable manner, preferably by hold-fast devices in the form of rivets 3.

The section 1, is dome-shaped in contour and is constructed of a highly polished metallic material. The material from which the section 1 is formed, not only has its outer face, but its inner face highly polished. The inner face of the section 1, provides a reflecting surface for directing heat rays, in the form of light, to the scalp for treating the latter. The section 1, medially thereof, at its top, is formed with an opening 5, and depending from the inner face of the section 1, as well as aligning with the opening 5, is a sleeve constituting a socket forming member 6, provided with internal threads 7. As shown, the member 6 is an integral part of the section 1, but if desired, it can be formed independently of and secured in any suitable manner to said section 1.

Detachably mounted in the member 6, as well as being suspended thereby within the section 1, is an electric lamp 8, of the incandescent type and which is formed with a contact element 9, of any suitable arrangement. Extended into the member 6, at the top thereof, is a removable contact plug 10, formed with a knurled flange 11 for conveniently handling the plug 10, and the latter is associated with the element 9 for electrically connecting the lamp 8 with a source of electrical energy, not shown. Current connections 12 inclosed by a casing 13, are carried by the plug 10, and said connections 12 terminate in a coupling member 14 to provide for detachably securing the current connections 11 with the electrical source.

The lower section 2 is constructed of fibrous material, that is to say, a material other than metal, preferably cardboard, which possesses the characteristics to pro-

vide for the said lower section being impervious to heat, moisture and water. The section 2, is hollow and frusto-conical in contour and has its bottom edge 15 sloping or tapering downwardly from the front to the rear of said section so as to provide for the section 2 properly fitting the head, that is to say, so the section 2 will inclose the back of the head, as well as the front thereof, when the head gear is mounted on the head of the patient.

The lower section 2 supports the upper section 1 and is substantially stiff to prevent collapsing thereof when supporting section 1. The section 2 is capable of yielding diametrically so as to conform to the shape of the head of the patient when the head gear is mounted in position.

When the head gear is mounted in operative position so as to inclose the head of the patient and the lamp 8 illuminated, the upper section 1, will direct the heat rays onto the scalp and the area of the latter confined within the lower section 2, will be heated and this application of heat will cause the scalp to relax and open the pores thereof, so that a medicant applied to the scalp will penetrate to the roots of the hair and further the action derived from the application of the heat rays on the scalp will cause the stimulation of blood circulation, open the sweat glands, destroy bacteria, as well as provide for the convenient removal of dirt and crustaceous formations, and further prepare the scalp for a scientific treatment for the development of the hair bulbs, papilla, glands, etc., and although the preferred embodiment of the invention is as disclosed and illustrated, yet it is to be understood that

changes can be had in the details of construction without departing from the scope of the invention as claimed.

What I claim is:—

1. An apparatus for treating the scalp comprising a body portion consisting of a hollow dome-shaped upper metallic heat directing section, and a diametrically yieldable lower frusto-conical head enclosing section conformable to the shape of the head when mounted thereon and providing a support for said upper section, said lower section substantially stiff to prevent the collapsing thereof when supporting said upper section, means for connecting the upper portion of the lower section to the lower portion of the upper section, and an electrical heat generating device arranged within said body portion.

2. An apparatus for treating the scalp comprising a body portion consisting of a hollow dome-shaped upper metallic heat directing section, and a diametrically yieldable lower frusto-conical head enclosing section formed of a non-metallic material and conformable to the shape of the head when mounted thereon, said lower section forming a support for said upper section and substantially stiff to prevent collapsing thereof when in supporting position, means for permanently connecting the upper portion of the lower section to the lower portion of the upper section, and an electrical heat generating device arranged within said body portion.

In testimony whereof, I affix my signature hereto.

ALOIS MERKE.
